MULTIPLE MANIFOLD FOR INTERNAL-COMBUSTION ENGINES.

1,289,425.

Specification of Letters Patent. Patented Dec. 31, 1918.

Application filed July 11, 1917. Serial No. 180,024.

To all whom it may concern:

Be it known that I, STEPHEN IVAN FEKETE, a citizen of the United States, residing at Detroit, county of Wayne, State of Michigan, have invented a certain new and useful Improvement in Multiple Manifolds for Internal-Combustion Engines, of which the following is a specification, reference being had therein to the accompanying drawings. 10 My invention relates to internal combustion engines and particularly to those having a plurality of working cylinders. The invention has for its object to provide a manifold combined with a carburetor which 15 may be manually controlled when the engine is being started so that the air passing through the carburetor will have a high velocity and therefore will tend to break up the liquid fuel completely into particles and 20 will carry the particles of fuel suspended in the air from the carburetor to the cylinders of the engine. The construction hereinafter described provides a plurality of air passages or manifolds from the carburetor to 25 the cylinders, said passages being of different cross sections, together with a gate or control valve by which one or more of the passages can be closed when the engine is being started. It will be understood that closing 30 of one or more of the said passages results in increasing the velocity of flow through the passage or passages which still remain open because all the air which passes into the engine must pass through a passage 35 of relatively small capacity. By reason of the high velocity, the heavy distillate cannot condense out and accumulate in a pool which is later carried over into the engine forming black smoke and a carbon deposit. 40 In the accompanying drawings I have shown my invention as combined with an internal combustion engine having overhead inlet valves but it will be understood that I do not limit myself to this construction as 45 my invention is also applicable to engines containing puppet or sleeve valves.

The invention will be fully understood by reference to the accompanying drawings taken in connection with the following description and the novel features thereof are pointed out and clearly defined in the claims at the close of this specification.

In the drawings, Figure 1 is a vertical section of a cylinder, manifold and carburetor embodying my invention.

Fig. 2 is a top plan view of the parts shown in Fig. 1 showing also the several cylinders of a six cylinder engine. Fig. 3 is a section on line 3-3, Fig. 2.

Fig. 4 is a section on the lines 4-4 of 60 Fig. 1.

Fig. 5 is a section on line 5-5 Fig. 1.

Referring now to the drawings at 11, 11 are shown the cylinders of an internal combustion engine. At 12 is shown one of the 65 inlet valves. In the case chosen it is located in the top of the cylinder head and the engine is of the overhead valve type. Surrounding the inlet valve 12, is a space 13 through which the gas flows to the cylinders 70 11. At 14 is shown a carburetor having a fuel jet 15 and air inlet 16. Within the chamber 17 formed on top of the carburetor is located a bell or piston 18 movable vertically so that its depending flanges intercept the air passage through the carburetor. The position of the bell is controlled in any convenient manner as, for instance, by a bell crank 19 pivoted at 20 to the top 75 of the carburetor and having one arm connected by link 21 with the bell 18 and the other arm by link 22 to a suitable handle, not shown, which is within the convenient reach of the operator. The carburetor 14 is connected by a manifold 23 with the said spaces 80 13, 13 which lead to the respective cylinders.

The manifold is in plan view of the ordinary well known shape. It is, however, divided into a series of parallel passages of different cross sections. In the form shown on 90 the drawings, there are three passages 24, 25 and 26. The lowest passage 24 is of the smallest cross section and passages 25 and 26 are each of larger cross section. In the portions of the manifold which are parallel 95 with the longitudinal axis of the engine, the cross sections are the shape shown in Fig. 3, that is, each of the passages composing the manifold is of substantially rectangular cross section. At the point where the carburetor and the manifold unite, see Fig. 4, the cross section is substantially triangular in shape, the three passages being separated from each other by webs 27 and 28. On the intake side of the carburetor the passage is 100 29 and 30.

From the foregoing description it will be seen that if the bell or piston 18 is lowered 105 so that its lower edge is adjacent the web 28, 110

the two passages 25 and 26 will be closed and the entire volume of air drawn into the engine at each revolution must pass through the small passage 24 with the result that the 5 air attains a high velocity carrying with it the fuel from the orifice 15 which it breaks up into small particles and which is prevented by the high velocity from condensing in the manifold or at the turns.

10 When the bell 18 is lifted until its lower edge is about opposite the partition 27, the passages 24 and 25 will be open and there will be a substantially uniform flow through both passages. When the bell is in its extreme 15 upper position, the engine is supplied through all three passages in the manifold.

The device, therefore, supplies a manifold of cross-section capable of being varied according to the requirements of the engine at 20 the given movement. It also provides means for introducing the explosive mixture at a high velocity without the use of a supplementary fuel jet.

What I claim is:

25 1. In combination with an internal combustion engine and a carbureter, a manifold leading from the carbureter to the engine and being in cross-section substantially triangular with the apex down, one or more

horizontal partitions extending lengthwise 30 of the manifold and dividing it into a plurality of passages of different cross sections, and a valve movable to intercept one or more of said passages.

2. In combination with an internal combustion engine and a carbureter, said carbureter having a substantially straight passage 35 of triangular cross section through it, a fuel jet in said carbureter, a manifold leading from the carbureter to the engine divided 40 into a plurality of passages of different cross sections, and a movable piston the lower edges of which intercept the said passages and close them successively.

3. In combination with an internal combustion engine and a carbureter having a jet, a manifold leading from the carbureter to the engine and being in cross section substantially triangular with the apex down, one or more horizontal partitions extending 50 lengthwise of the manifold and dividing it into a plurality of passages of different cross sections, the jet of the carbureter being in line with the passage of least cross section, and a valve movable to intercept one or more 55 of said passages.

In testimony whereof I affix my signature.

STEPHEN IVAN FEKETE.
